WILLIAM A. TEBO, OF ANTHONY, RHODE ISLAND, ASSIGNEE TO DRAFTER CORPORATION, OF HOPEDALE, MASSACHUSETTS, A CORPORATION OF MAINE.

AUTOMATICALLY THREADING SHUTTLE FOR LOOMS.

Application filed July 23, 1928. Serial No. 295,915.

This invention relates to automatically threading shuttles for looms and is more particularly directed to means for locking the thread in the side delivery eye that the shuttle 5 may not become unthreaded.

It is now the common practice to provide automatically threading shuttles for looms with overhangs, guards and other devices to prevent the shuttle from becoming unthreaded during weaving operations, but notwithstanding the general purpose of such guards and overhangs their object has often failed to be accomplished in actual weaving.

The object of the present invention is to 15 provide an automatically threading shuttle with means which will permit the shuttle to be automatically threaded while in the loom and thereafter to lock the thread in shuttle threaded position.

20 In accordance with the present invention, the shuttle is provided with a thread lock which crosses the thread passage leading to the side delivery eye and cooperates with the usual downwardly extending horn of the 25 threading block to prevent upward movement of the thread from the side delivery eye when once the shuttle has been completely threaded. More specifically stated, the thread lock of the present invention is provided with a slot 30 or opening into which a part of the threading block, such, for instance, as the horn, extends, the construction being such that once the thread has passed through the thread passage leading to the side delivery eye, it is 35 thereafter locked in the side delivery eye to lead under the horn.

The invention and novel features thereof will best be made clear from the following description and the accompanying drawings 40 of one good form thereof.

In the drawings:

Fig. 1 is a perspective view of an automatically threading shuttle, showing more particularly the eye end thereof, provided 45 with the present invention;

Fig. 2 is a sectional side elevation on an enlarged scale showing the thread lock and horn in their normally operative position;

Fig. 3 is a front elevation of the threading 50 block and thread lock looking from the front of the shuttle;

Fig. 4 is an underside view of the lock and thread block;

Fig. 5 is a perspective view showing the

threading block and its associated relation 55 with the thread lock; and

Fig. 6 shows a modification.

The shuttle 1 may be of the usual automatically threading type provided with the bobbin 60 chamber 2 frontward of which the shuttle is provided with a thread block receiving chamber 3 in which the threading block 4 is positioned and held by means of the usual transversely extending screw 5. The shuttle is 65 provided with the usual longitudinally extending thread passage 6 and side delivery eye 7 which communicates therewith.

The threading block may be of any of the usual types of such blocks provided with a 70 downwardly extending horn, the lower portion of which overlies the thread and directs it to the side delivery eye during the weaving operation. The threading block provides a thread passage leading from the top portion 75 of the shuttle to the side delivery eye to permit the thread to pass downwardly to the side delivery eye on the second pick of the shuttle after filling replenishment.

In the present instance of the invention, the 80 threading block 4 has the usual longitudinal thread passage 6 formed between the side walls of the threading block, as indicated in Fig. 3, and at the front portion of the threading block is a thread director 8 between which and the wood of the shuttle, at 9, is formed a 85 thread passage 10 leading downwardly to the side delivery eye 7.

Extending downwardly from the top portion 90 of the threading block is the horn 11 preferably formed with a guiding surface 12 under which the thread passes on its way to side delivery eye during weaving. It is sometimes desirable to provide the threading block with a stud 13 to engage an opening 14 in the 95 shuttle to assist in positioning and holding the threading block in place. As thus far described, the threading block may be of usual construction and the wood of the shuttle may be cut away or removed at 15 leading towards the tip end of the shuttle, to provide a thread leader, the construction being such that upon the first pick of the shuttle following replenishment, the thread will be drawn from the 100 filling carrier in the shuttle and enter the recess or cut away portion 15 and on the next pick of the shuttle the thread will be drawn downwardly through the thread passage 10 into the side delivery eye 7, whereupon the

105

shuttle is completely threaded. The present invention provides means for locking the thread in the side delivery eye under the horn of the threading block so that it may not escape upwardly therefrom after the shuttle has once been completely threaded.

The thread lock crosses the thread passage leading to the side delivery eye and is provided with an opening or slot into which a part of the horn, in the present instance, projects. The thread lock 16 may be variously secured in place and as shown may have a base portion 17 underlying the thread block 4, and, if desired, have an opening 18 through which the stud 13 may project to assist in holding the thread lock in position.

The thread lock 16 extends upwardly from a point below the horn 11, as indicated in Fig. 2, and between its lower and upper portions it is provided with an opening or slot 19 into which a part of the horn, as at 20, extends. In most cases the part 20 of the horn, which is downwardly curved, as indicated, may project through the slot or opening 19 of the thread lock. The point 21 of the horn may extend through the slot or opening of the thread lock and terminate above the lower portion of the opening or slot, the construction being such that on the second pick following replenishment the thread will pass downwardly in the thread passage 10 and be deflected through the slot 19 of the lock about the downwardly curved portion of the horn, as indicated at *a*, Fig. 5. As the tension of the thread thereafter pulls it downwardly in the direction of the side delivery eye, it finally will take position below the arched portion 12 of the horn and extend to the side delivery eye 7, and thereafter any upward movement of the thread tending to cast it out of the thread passage 10 will be prevented by the overlapping relation of the slotted thread lock 16 and the downwardly extending horn. The slot of the thread lock constitutes an important feature of the present invention, and while formed as a slot, it is obvious, of course, that one side portion or wall of the slot may be omitted, the essential in this respect being that the thread lock and horn shall overlap in the thread passage 10 with sufficient space between the two to permit the thread to pass downwardly to the side delivery eye and then prevent its subsequent bodily upward movement through the thread passage.

The thread lock 16 extends in an inclined direction across the thread passage 10 and its end portion 22 is preferably seated in a recess 23 formed in the wood of the shuttle, thereby obviating any danger of the thread catching on the end of the thread lock as it passes downwardly in the thread passage 10.

A pin 24 may be conveniently employed, as indicated in Fig. 2, so that the thread may lead about the pin during its delivery from the shuttle, and the pin 24 may be provided

with an end portion 25 extending into the hole 26 formed in the thread lock, thereby further assisting in holding the thread lock in its normally operative position during the shocks to which the shuttle is subjected during the weaving operation.

Instead of securing the base portion 17 of the thread lock in the manner hereinbefore described and as shown by Fig. 2, the base portion of the thread lock may be otherwise secured in place, as indicated, for instance, in Fig. 5, wherein the base portion is secured to the threading block or stud 13 by solder or the like, as indicated at 27.

The essential feature of the thread lock of the present invention consists in its overlapping relation with the horn of the threading block so that while the thread may pass downwardly in the thread passage 10 and be deflected about the horn and thread lock, it will eventually take a position where its upward movement will be prevented by the overlapping relation of the horn and thread lock.

While the slotted character of the thread lock 16 is found to be a good practical form of the invention, it is obvious that variations may be made in the thread lock to carry out the essential features of the invention, and one of such variations is indicated in Fig. 6 wherin the thread lock is formed as a single unslotted upwardly inclined member 28 in overlapping relation with the downwardly extending horn, sufficient space being provided between the two to permit the thread to pass downwardly below the horn into the side delivery eye, from which its escape is rendered impossible during the weaving operation.

What is claimed is:

1. An automatically threading loom shuttle having a side delivery eye, a threading block forming a side threading passage leading to the side delivery eye and provided with a downwardly extending horn, and a thread lock extending in an inclined direction across the side threading passage in overlapping relation with the lower point of the horn and having its lower and upper ends resting on the wood of the shuttle at opposite sides of the side threading passage.
2. An automatically threading loom shuttle having a side delivery eye, a threading block forming a threading passage leading to the side delivery eye, a thread lock having one end secured at the lower portion of the threading block and its other end seated in the shuttle wood above the lower portion of the block at the opposite side of the thread passage leading to the side delivery eye and provided with a slot, and a horn extending downwardly from the top of the block with its lower point extending into the slot of the lock.
3. An automatically threading loom shut-

tle having a side delivery eye, a threading block forming a side threading passage leading to the side delivery eye, a thread lock crossing the thread passage in an inclined direction with its lower end secured at the lower part of the block adjacent the side delivery eye and its upper end seated in the wood of the shuttle at the opposite side of the thread passage and provided with a slot 10 or opening between its ends, and a horn extending downwardly and backwardly from the upper part of the block with its point projecting into the opening or slot of the lock.

15 4. An automatically threading loom shuttle having a side delivery eye, a threading block forming a side threading passage leading to the side delivery eye, a horn extending downwardly and backwardly from the top 20 of the block and having a thread guiding surface under which the thread is delivered to the side eye, and a thread lock having its lower end secured at the lower part of the block and crossing the thread passage in overlapping relation with the point of the horn with the upper end of the lock seated in the wood of the shuttle above the point of the horn at the opposite side of the threading passage to prevent upward movement of the 25 thread from the side delivery eye.

5. An automatically threading loom shuttle having a side delivery eye, a thread director forming a threading passage leading to the side delivery eye, a horn extending downwardly and backwardly from the thread director and having a pointed lower end under which the thread passes during threading, a thread guiding surface formed at the lower part of the horn back of the pointed end thereof, a thread lock secured to the shuttle below the end of the horn and thread on its way to the side delivery eye and extending upwardly in overlapping relation with the pointed end of the horn with its upper end seated in the wood of the shuttle at the opposite side of the threading passage and frontward of the horn.

40 6. An automatically threading loom shuttle having a side delivery eye and a threading passage leading to the side delivery eye, a thread lock secured adjacent the bottom of the threading passage and extending upwardly across said passage with its upper end

seated in the wood of the shuttle at the opposite side of said passage and provided with an 55 opening between its ends, and a horn having a part projecting into said opening and cooperating with the thread lock to prevent upward escape of the thread from the side delivery eye.

60 7. An automatically threading loom shuttle having a threading block provided with a horn extending downwardly and backwardly from the top of the block and a thread director forming a thread passage leading to the side delivery eye, and a thread lock extending across the thread passage from below the end of the horn and having an elongated opening through which the lower portion of the horn extends with sufficient space between to permit deflection of the thread about the horn on its way to the side delivery eye as the shuttle is completely threaded.

75 8. An automatically threading loom shuttle having a side delivery eye and a thread passage leading to the side delivery eye, a horn extending downwardly and backwardly from the top of the thread passage under which the thread leads to the side delivery eye during weaving, a thread lock extending 80 from a point below the horn and crossing the thread passage in overlapping relation with the horn, the upper end of the thread lock being seated in the wood of the shuttle at the front of the thread passage to prevent catching the thread as the latter moves towards the side delivery eye.

85 9. An automatically threading loom shuttle having a side delivery eye and a thread passage leading to the side delivery eye, a 90 threading block having a longitudinal thread passage and a downwardly extending pointed horn under which the thread leads to the side delivery eye during weaving, a separate thread lock secured at and extending from a 95 point rearward of and below the horn and crossing the thread passage leading to the side delivery eye in overlapping relation with the horn, and a pin back of the horn and the crossing point of the thread lock and horn 100 and forming with the horn and thread lock a lead for the thread between them during weaving.

In testimony whereof, I have signed my name to this specification.
